UNITED STATES PATENT OFFICE.

CORNELIUS FLORA, OF SCHENECTADY, NEW YORK.

DESIGN FOR AN EMBLEM.

No. 38,362.

Specification for Design.

Patented Dec. 18, 1906.

Application filed October 15, 1906. Serial No. 339,118. Term of patent 3½ years.

To all whom it may concern:

Be it known that I, CORNELIUS FLORA, a citizen of the United States, residing at Schenectady, in the county of Schenectady and State of New York, have invented a new, original, and ornamental Design for an Emblem, of which the following is a specification, reference being had to the accompanying drawing, forming part thereof.

The figure is a plan view of the design.

I claim—

The ornamental design for an emblem, as shown.

CORNELIUS FLORA.
